UNITED STATES PATENT OFFICE.

JOHN H. LUCKEY, OF NEW YORK, N. Y.

SAFETY DEVICE FOR AIR-BRAKES.

SPECIFICATION forming part of Letters Patent No. 746,969, dated December 15, 1902

Application filed July 15, 1903. Serial No. 166,634. (No model.)

To all whom it may concern:

Be it known that I, JOHN H. LUCKEY, a citizen of the United States, and a resident of New York city, in the county of New York and State of New York, have invented certain new and useful Improvements in Safety Devices for Air-Brakes, of which the following is a specification.

The subject of this invention is an improved safety device for air-brakes, and is more particularly designed for service in connection with electric-motor cars, although it will be equally useful in other applications where air-brakes are employed.

15 A primary object of the invention is to provide a simple and efficient arrangement that can be readily adjusted to existing constructions of air-brakes apparatus and which will insure the automatic application of the brake when the motorman for any reason becomes incapacitated, especially when in a standing position, and fails to maintain his foot in a definite position. I so construct and organize the essential parts constituting my improvement that operation on the part of the motorman will be accomplished by one foot, and consequently hand-controlled means are avoided and the automatic capacity of the device therefore more positively assured, as 30 will fully appear hereinafter.

With the above and other purposes in view the invention comprises generally an auxiliary valve communicating with the air-release pipe and adapted to be maintained closed solely by a pedal or foot-lever suitably located for serving for a foot-rest and permitting the motorman to keep one foot thereon, the removal of such foot resulting in the air from the release-pipe acting to unseat the 35 auxiliary valve, escape to the atmosphere, and thereby cause the setting of the brakes, as will be readily comprehended by those familiar with this art.

There are other important features connected with the invention, which in addition to those previously alluded to are clearly described in the subsequent detailed description.

In the accompanying drawings, forming 45 part of this specification, Figure 1 is a vertical elevation, partly in section, of so much

of the air-brake equipment of an electric-motor car as is required to illustrate my invention. Fig. 2 is a sectional plan view of Fig. 1, the section being taken in the plane 55 indicated by the broken line 2 2 of said latter figure. Fig. 3 is a detail sectional view showing, on an enlarged scale, the auxiliary valve and certain immediate parts. Fig. 4 is a detail view of the guide for limiting the movement of the foot-lever.

Vertically located in the motor cab or compartment at the end of the car are the pipes A B, the former of which communicates with the compressed-air reservoir and serves in 65 connection with the hand controlling-valve C, which is properly ported, to release the air through the train-line pipe B and accomplish the application of the brakes when desired. The casing of the valve C is suitably braced 70 relative to the car-wall D through the medium of the bracket d and connection d'.

Included within the upper portion of the pipe B is a T-coupling B', the lateral branch of which is connected with the upper bend e 75 of the pipe E, the latter being compactly disposed within the cab-compartment and provided at its lower end with a horizontal bend e', located close to the car-floor G'. This bend e' comprises a vertically-descending turn e², so which passes through the car-floor and is adapted to discharge into the atmosphere.

Introduced into the bend e' is a puppet globe-valve F, secured air-tight in position by suitable coupling provision and having 85 its valve F' seated in opposition to the pressure of the air flowing downwardly through the pipe E. The stem f of the valve F' plays through the stuffing-box f' at the upper side of said valve and has a bifurcated head f² receiving the contiguous portion of the horizontal lever G, said head f² being movably connected with said lever by a pin g, passing through the bifurcated head f² and engaged within a longitudinally-extended slot g' in 95 the adjacent portion of the lever. One end of the lever is pivotally secured at the upper end h of a standard H, preferably carried by the branch e' near the globe-valve or otherwise. The lever G extends between and beyond the pipes A B and carries at its free end a foot-rest or pedal G². This pedal I prefer

to make of a rounded contour throughout its entire upper surface.

I refer to a vertical guide consisting of a strap of metal bent to form the forward horizontal upper portion extending above the lever to limit the upward movement thereof.

From the description thus far it will be comprehended that in running the car the motorman occupies a position with one foot supported upon the pedal G², so as to maintain the valve F' closed and prevent the escape of air by way of the pipe E. Now if for any reason the pedal G² should be relieved from foot-pressure the air in the pipe E will operate to unseat the valve F' and escape to the atmosphere, and thus result in the setting of the brakes. The slot g' in the lever G provides for a varying engagement between the valve-stem and said lever due to the changing position of the lever in its pivotal movements. It will be obvious, however, that the unseating movement of the valve being in a direction at an angle to that in which the slot extends will always permit the actuation of the valve without enabling the pressure of the air to undesirably unseat the same. With a view of insuring the valve F' seating airtight and avoiding any grinding of the valve due to undue pressure on the foot-lever I prefer that said valve shall be of yielding material or at least have yielding bearing faces.

A plug-valve B², interposed in the train-line pipe near the coupling B', provides for cutting out the pipe E and its auxiliary valve when desired.

From the foregoing it will be readily appreciated that my improved device is not only highly useful and simple, but it combines with the ordinary brake apparatus an element of safety, highly desirable particularly in the matter of electric-motor cars. The rounded contour of the upper portion of the pedal G² necessitates a certain amount of care on the part of the motorman in order to properly maintain his foot thereon. Consequently if such motorman should become suddenly ill or otherwise incapacitated the rounded contour referred to would the more readily insure his foot slipping from the pedal, and thereby occasion the application of the brake. Ordinarily the weight of the leg and foot of the motorman will be sufficient to keep the valve closed against the train-line pressure without requiring special effort on the part of the motorman.

I do not desire to be understood as limiting myself to the precise construction and arrangement of parts shown and set forth, but reserve the right to such modifications as

may be fairly considered within the scope of 60 my invention.

Having now described my invention, what I claim as new, and desire to secure by Letters Patent, is—

1. A safety device for air-brake apparatus, 65 comprising a branch pipe communicating with the train-line pipe and with the atmosphere, said branch pipe having a valve interposed in its lower portion and seating in opposition to the pressure of the air in the 70 branch pipe, and a lever connected with said valve and solely depressible by a foot-pedal.

2. A safety device for air-brake apparatus, comprising a branch pipe communicating with the train-line pipe and with the atmosphere, 75 said branch pipe having a lower bend arranged in a plane between the pressure and train-line pipes and contiguous to the floor, a valve interposed in said lower bend and seated in opposition to the pressure of the air 80 in the branch pipe, a lever operatively connected with said valve and extending between the pressure and train-line pipes, said lever being depressible solely by a foot-pedal.

3. A safety device for air-brake apparatus, 85 comprising a branch pipe communicating both with the train-line pipe and the atmosphere, and having a lower bend located contiguous to the floor, a valve interposed in said bend and provided with a yielding seat-engaging 90 surface, and a lever for closing said valve and provided with a foot-pedal.

4. A safety device for air-brake apparatus, comprising a branch pipe communicating with both the train-line pipe and the atmosphere, 95 said branch pipe including a lower bend contiguous to the floor, a valve located in said bend and seating in opposition to the pressure of the air in said branch pipe, and a lever for closing said valve and provided with 100 a pedal having an upper rounded surface.

5. A safety device for air-brake apparatus, comprising a branch pipe communicating both with the train-line pipe and the atmosphere, 105 said branch pipe including a lower bend contiguous to the floor, a valve interposed in said bend and seating in opposition to the air in said branch pipe, a pivoted lever having a slot, and a pin within said slot and connected with the valve-stem.

Signed at city of New York, in the county of New York and State of New York, this 7th day of July, A. D. 1903.

JOHN H. LUCKEY.
